UNITED STATES PATENT OFFICE.

GIUSEPPE MUSCATO, OF BUFFALO, NEW YORK.

ATTACHMENT FOR WASH WRINGERS.

Application filed May 21, 1927. Serial No. 193,189.

This invention relates to improvements in clothes wringers and more particularly to a combined guard and conveyor for feeding the garments to the wringer.

One of its objects is the provision of a simple and efficient attachment of this character which is designed to deliver the clothes to the wringer and thereby prevent the operator's hands being accidentally caught between the wringer-rolls.

A further object of the invention is to provide a wringer attachment which is so constructed and organized that it is readily reversible for use in wringing clothes as they come from the washing machine or from the wash tubs.

A still further object is to provide the combined guard and conveyor with means for guiding and directing the water wrung from the clothes in a predetermined course.

In the accompanying drawings:—Figure 1 is a front view of a wringer equipped with my improvement. Figure 2 is a vertical section thereof on line 2—2, Figure 1. Figure 3 is a top plan view of the same, partly in section. Figure 4 is an enlarged transverse section on line 4—4, Figure 3.

Similar characters of reference indicate corresponding parts throughout the several views.

By way of example, the improved attachment is shown in connection with a well-known type of wringer 10 applied to a washing machine 11 and including the customary rolls 12, 12 journaled in the side walls 13 of the wringer-frame and driven in opposite directions by gearing 14.

The means for conveying or feeding the clothes between the wringer-rolls and forming a safety guard for preventing the hands of the operator being caught between said rolls comprises a longitudinally adjustable frame movable in a horizontal plane relative to the rolls 12 and carrying a conveyor. Said frame preferably consists of a pair of parallel slide bars 15 guided in openings 16 formed in the side walls 13 of the wringer below its rolls to assume either the full line or dotted line position shown in Figure 2. Located at the opposite ends of these slide

bars and journaled in suitable bearings 17 applied thereto are rolls 18, 18 parallel with the wringer-rolls and about which passes the conveyor consisting of an endless belt 19 of any appropriate material, such as rubber or the like. This belt is driven in either direction by the wringer-rolls and for this purpose its upper stretch passes between said rolls, as indicated in Figure 2. The conveyor-frame may be positively held in either of its operative positions by means of spring-pressed bolts 20 which are mounted in the side walls 13 of the wringer-frame and engage corresponding locking openings 21 in the slide bars 15, as shown in Figure 4.

In order to prevent the water wrung from the clothes splashing over the side edges of the belt and on to the floor, it is provided along its marginal edges with retaining strips 22 which retain the water on the belt and compel it to flow into the wash tub or the tub of the washing machine.

To further guard the hands of the operator from accidentally coming in contact with the wringer-rolls, hinged plates 23 are mounted transversely of the wringer-frame above and on each side of these rolls. These guard plates extend outwardly and downwardly from their hinges 24, as shown in Figure 2, and terminate a suitable distance above the face of the belt 19. By this construction, the guard plates also function to prevent bunching of the clothes before being admitted to the wringer-rolls.

By mounting the conveyor on an adjustable frame in the manner described, the same can be made very compact and of a minimum length, and it can be quickly shifted to a position over the tub of the washing machine or to a position over the wash tubs. While possessing these advantages, it does not in any way interfere with the movement of the wringers of the swivel type now in common use on electric machines, and it can be manufactured at a moderate cost.

I claim as my invention:—

In combination, a wringer provided with rolls and having openings in the side walls thereof arranged below and at right angles to the axes of said rolls, a frame including tubu-

lar slide rods guided in said wall-openings for movement in a horizontal plane, said slide rods having locking openings adjacent their ends, bearings applied to the ends of said slide rods, rolls disposed at the opposite ends of said frame and journaled in said bearings, an endless belt passing around said frame-rolls and having its upper stretch disposed between the wringer-rolls, and spring-pressed locking bolts in the side walls of the wringer for detachably engaging the locking openings in said slide rods for holding the frame in a plurality of positions relative to the wringer-rolls. 10

GIUSEPPE MUSCATO.
